J. A. ROCHE

AIRPLANE FUSELAGE CONSTRUCTION

Filed April 18, 1924

FIG. 1.

FIG. 2.

INVENTOR
Sean A. Roche

BY

Robert H. Young ATTORNEY

UNITED STATES PATENT OFFICE.

JEAN A. ROCHÉ, OF DAYTON, OHIO.

AIRPLANE-FUSELAGE CONSTRUCTION.

Application filed April 18, 1924. Serial No. 707,381.

To all whom it may concern:

Be it known that I, JEAN A. ROCHÉ, a citizen of the United States, residing at Dayton, in the county of Montgomery and State of Ohio, have invented certain new and useful Improvements in Airplane-Fuselage Constructions, of which the following is a specification.

This invention relates to improvements 10 in fuselage constructions for airplanes, and is especially concerned with the provision of a simplified construction resisting compression, tension, bending, and torsion loads.

The principal object of the invention is 15 to provide a fuselage construction dispensing with the usual elaborate heavy framework, and utilizing upper and lower main longérons joined to criss-cross struts for assuming compression and tension loads, and 20 having tensioned stay wires extending about the frame-work to assume the loads which tend to bend or twist the framework.

The invention is illustrated in the accompanying drawing, in which:

25 Fig. 1 is a perspective view of the tail-end of a fuselage shown devoid of covering in order to disclose the construction of the framework.

Fig. 2 is an isolated view of one of the 30 criss-cross struts used in the construction.

The present fuselage construction comprises two main longérons 10 and 11 joined by fittings 12 to the upper and lower ends of vertical struts 13. The vertical struts 13 35 have horizontal struts 14 secured by suitable fittings 15 intermediate their ends. The horizontal struts are joined to secondary or auxiliary longérons 15' at the sides of the framework by fittings 16. The members thus far mentioned assume compression and tension loads. The torsion and bending loads 40 are assumed by a plurality of stay wires 17 which are tensioned suitably by turn buckles 18. The stays 17 it will be noted, extend 45 from the junction of a vertical strut 13 at one station with either of the longérons 10 or 11 diagonally past an intermediate station to the junction at the next station of a vertical strut 13 with the other longeron. To clarify 50 this point, the two portions of a continuous wire extending, in the manner above stated, are lettered A and another wire extending criss-cross to the first wire and connected in a similar manner is lettered B in the drawing. 55 The wires criss-cross at their mid point

at the junction of a horizontal strut 14 and auxiliary or secondary longeron 15. Any strain axially or transversely of the framework is assumed by the stays 17 so that a very sturdy construction is afforded despite 60 the fact that a very small number of parts are used as compared with the usual fuselage frame construction.

The stabilizer 19 and tail fin 20 together 65 with the elevator 21 and rudder 22 are conveniently mounted on the end of the longeron 10 and the vertical strut 13 at the outer end of the framework. This portion of the construction however forms no part of the present invention. If desired, fairing 70 strips to give form to the fuselage may be supplied between the longérons in a manner well understood in the art.

I claim:

1. In an aircraft construction, a plurality 75 of criss-cross struts, longitudinal members joined to said struts, and stays extending diagonally from the junction of a strut and longitudinal member at one station, to the junction with another longitudinal member 80 at another station of a strut transverse with respect to the last mentioned strut.

2. In a fuselage construction for airplanes, and upper and lower main longeron, vertical 85 struts joined thereto, horizontal struts joined to said vertical struts, secondary longérons joined to the horizontal struts, and a stay extending from the junction of a vertical strut and one of said main longérons at one station, diagonally past an intermediate 90 station to the junction at another station of another vertical strut with the other of said main longérons, the stay at said intermediate station extending through the junction there of the horizontal strut of that station with 95 one of said secondary longérons.

3. In a fuselage construction for airplanes, an upper and lower longeron, vertical struts joined thereto, horizontal struts joined to 100 said vertical struts, secondary longérons joined to the horizontal struts, and a stay extending from the junction at one station of a vertical strut and longeron, past an intermediate station to the junction at the next station of a vertical strut and longeron, and 105 engaging the horizontal strut of the intermediate station at its junction with a longeron.

4. In an airplane fuselage construction, 110 an upper and lower longeron, vertical struts

joined thereto, horizontal struts joined to said vertical struts, secondary longérons joined to the horizontal struts, and tensioned stay wires extending in criss-cross relation 5 from the junction at opposite ends of a vertical strut with the two main longérons, past an intermediate station to the next station to the junction at opposite ends of the vertical strut there with the two main longérons, said stays engaging at the points of 10 crossing at the junction of the horizontal

strut of the intermediate station with the secondary longérons.

5. In an airplane fuselage, an upper and lower longéron and struts extending vertically between the same for compression and tension loads, transverse members on said struts and tensioning means extending between said members and said struts and longérons for torsion and bending loads. 15

In testimony whereof I affix my signature.

JEAN A. ROCHE. 20
